UNITED STATES PATENT OFFICE.

JOHN E. WOFE AND THOMAS BROWNING, OF GASSAWAY, WEST VIRGINIA.

ARTIFICIAL FOOT.

1,151,144.

Specification of Letters Patent. Patented Aug. 24, 1915.

Application filed December 19, 1914. Serial No. 878,123.

To all whom it may concern:

Be it known that we, JOHN E. WOFE and THOMAS BROWNING, citizens of the United States, residing at Gassaway, in the county 5 of Braxton and State of West Virginia, have invented new and useful Improvements in Artificial Feet, of which the following is a specification.

This invention relates to artificial feet of 10 the pneumatic type, in which the body of the foot is composed of a bag or sack filled with compressed air, whereby a desired air-cushion effect is obtained.

The primary object of this invention is to 15 provide an air cushioning foot which is simple, light, durable and inexpensive capable of being readily repaired, and applicable to any ordinary type of artificial leg.

A further object of the invention is to 20 provide an artificial foot of maximum strength and resiliency to sustain and reduce to a minimum the strains and jars transmitted to the leg in walking.

The invention consists of the features of 25 construction, combination and arrangement of parts herein fully described and claimed, reference being had to the accompanying drawings in which:—

Figure 1 is a side elevation of an artificial 30 leg to which our improved foot is shown applied. Fig. 2 is a sectional view thereof.

Fig. 3 is a perspective view of the foot detached. Fig. 4 is a vertical longitudinal section through the foot. Fig. 5 is a transverse 35 section thereof on the line 5—5 of Fig. 4. Fig. 6 is a view of the air sack removed. Fig. 7 is a similar view of the inner casing as arranged to inclose the sack and to be applied to the outer casing. Fig. 8 is a view of 40 the saddle. Fig. 9 is a view of the instep piece. Fig. 10 is a section through the applied foot on the line of the ankle joint.

Referring to the drawing, 1 designates an 45 artificial leg of any ordinary or preferred construction, and 2 our improved air cushioned foot.

The foot comprises an elastic bag or sack 3 of rubber or other suitable material, shaped to suit the contour of the foot, and 50 filled with air under a desired pressure. This bag or sack 3 is provided with a valve filling tube 4 which is designed to extend upwardly through the foot and into the leg and have its inlet end exposed at some suitable point in the leg, so that the bag or sack

may be recharged with air when occasion requires.

The said bag or sack 3 is inclosed within an inner casing 5, of some strong and durable protective material, such as canvas or 60 canvas and rubber, said inner casing providing a protecting envelop to reinforce and guard the elastic bag from injury. The said inner casing is of a shape corresponding to the bag and is provided along its upper posterior portion with an opening 6 normally held closed by a lacing thong 7, through which opening the bag or sack may be applied and removed. The marginal edges of the opening are cut away at a point for the 65 outward passage of the valved end of the charging tube or connection 4, and pass around and are suitably secured to the inner casing, in front and rear of this arch or instep portion, are straps 8 of webbing or 70 other suitable material which are fastened at their free ends to the eyes 9 of connecting members or bolts 10. These connecting members or bolts 10 extend upwardly within suitable recesses in the leg 1, in which 75 they are slidably mounted, said bolts or connecting members being retained in position and limited in motion by nuts 11. Coiled springs 12 surround bolts between the same and abutments on the leg, whereby the bolts 80 are permitted to have a restrained yielding movement, to adapt the foot to have upper play or articulation on its ankle pivot, hereinafter described. In some cases the springs 85 12 may be dispensed with, as the elastic bag 90 or sack will give the desired resiliency and cushioning action.

The webs or straps 8 pass upward through notches 13 in the marginal edges of a saddle 14, comprising a concavo-convex body of 95 some light, strong and durable material, such as wood fiber, which is riveted or otherwise firmly fastened along its marginal edges, as shown at 15, to the sides of an ankle piece 16, preferably made of the same material, and which gives the proper shape to the ankle portion of the foot and adapts the same for application to the leg 1. By this construction it will be observed that the lower portion of the foot is made of an air 105 cushioned body, while the upper portion of the foot is made of a strong and durable, and yet light, structure which is adapted to sustain the shocks and jars falling upon the foot and during walking action, the greater 110

proportion of which shocks and jars are cushioned by the pneumatic body of the foot, whereby stresses and strains falling upon the leg 1 are reduced to the minimum. An 5 outer casing 17, formed of soft leather or some other suitable strong and durable material, is provided to receive and inclose the parts of the foot formed as above described, this outer casing is preferably pasted or 10 otherwise suitably secured to the sides of the instep piece. The bottom of the outer casing is provided with a longitudinally extending slit 18 normally closed by a lacing thong 19, such slit providing an opening 15 to admit of the ready insertion and removal of the air sack and inner casing, whereby ready facility for making repairs and replacing worn out parts is afforded.

Riveted to the ankle piece are armed eye 20 brackets 20, the eyes of which pivotally engage screws 21 fitting within the internally threaded ends of a tubular pivot bolt 22 carried by the leg 1, whereby the foot is detachably mounted in position upon the leg, so 25 as to be applied to any ordinary leg, and is permitted to have the usual ankle joint motion.

It will be evident from the foregoing description that our invention provides an artificial foot, which is not only of simple construction, and capable of application to any ordinary artificial leg, but which is strong, durable and light in weight, capable of being easily and conveniently repaired, and adapted to afford maximum resiliency for an easy cushioning action. By the construction described the air sack is inclosed and protected from injury without material interference with its resilient qualities.

40 We claim:—

1. An artificial foot comprising a pneumatic sack, a flexible casing therefor, within which the sack is removably inclosed, a rigid ankle piece, means for pivotally attaching 45 the same to a leg, and an outer casing secured to the ankle piece and having a bottom opening through which the sack and inner casing may be inserted and removed.

2. An artificial foot comprising a pneumatic sack, a flexible casing inclosing the same, an outer flexible casing inclosing the sack and inner casing, a saddle overlying the ankle portion in the inner casing and sack, an ankle piece to which the saddle and outer 55 casing are secured, and means for pivotally

connecting said ankle piece to an artificial leg.

3. An artificial foot comprising a pneumatic sack, an inner flexible casing inclosing the sack, an outer flexible casing inclosing the sack and inner casing and from which the same may be removed, a saddle of rigid material overlying the ankle portion of the sack and inner casing, an ankle piece secured to the saddle and outer casing, means 65 for pivotally connecting the ankle piece with a leg, straps engaging the inner casing and extending outwardly through said ankle piece, and means for resiliently connecting said straps with the leg in front and rear 70 of the pivotal connection.

4. An artificial foot comprising a pneumatic sack, a fabric inner casing inclosing the same and having a top aperture through which said sack may be applied and removed, an outer casing of flexible material inclosing the sack and inner casing and provided with a bottom opening through which said sack and inner casing may be applied and removed, a rigid saddle overlying the 80 ankle portion of the inner casing and inclosed within the upper portion of the outer casing, and a rigid ankle piece fixed to said saddle and outer casing.

5. An artificial foot comprising a pneumatic sack, an inner casing of flexible material inclosing the sack and having a top opening through which the sack may be applied and removed, an outer casing of leather inclosing the sack and inner casing and having a bottom opening through which the same may be applied and removed, a concavo-convex rigid saddle overlying the inner casing, a rigid ankle piece pivoted to the saddle and suitably fastened to the outer 95 casing, said saddle being provided with notches in its lateral edges, brackets upon the ankle piece for pivotal connection with the ankle bolt of a leg, and straps passed around the inner casing and extending outwardly through said notches and the ankle piece, and connections for yieldingly attaching said straps to the leg.

In testimony whereof we affix our signatures in presence of two witnesses.

JOHN E. WOFE.

THOS. BROWNING.
